UNITED STATES PATENT OFFICE.

MICHEL BECKER, OF NEW ORLEANS, LOUISIANA.

DESIGN FOR A SCHOOL-KNAPSACK.

SPECIFICATION forming part of Design No. 17,791, dated October 18, 1887.

Application filed February 14, 1887. Serial No. 227,513. Term of patent 7 years.

To all whom it may concern:

Be it known that I, MICHEL BECKER, a citizen of the United States, residing at New Orleans, in the parish of Orleans and State of Louisiana, have invented certain new and useful Improvements in a Design for a School-Knapsack; and I do hereby declare the following to be a full, clear, and exact description of the invention, such as will enable others skilled in the art to which it appertains to make and use the same.

Figure 1 is a perspective view of the rear portion of the knapsack when the same is being worn, and Fig. 2 is a like view of the front portion thereof.

The leading features in my design consist in rosettes arranged, respectively, on the straps and bottom of the knapsack and a novel configuration of suspending-loop. Of these rosettes two large ones are represented by the letters A A, arranged on the straps on the rear of the knapsack, as shown. Two small rosettes or stars, c c, are attached to straps on

the front side of the knapsack and four more of a like character are placed on its bottom. 25

The suspending-loop of the knapsack B is flat on its front and rear surfaces, but its top, bottom, and sides have the configuration of semicircles, as represented, said bottom being partially bifurcated. 30

Having described my invention, what I claim is—

The design for a knapsack herein shown and described, consisting of the knapsack B, the rosettes A A on the straps, the stars or rosettes C C C C C C, arranged, respectively, on the straps and on the bottom, and the top loop having parallel flat sides and circular top, sides, and bottom. 35

In testimony whereof I affix my signature in presence of two witnesses.

MICHEL BECKER.
